UNITED STATES PATENT OFFICE.

BRUNO SCHMELZER, OF JERSEY CITY, NEW JERSEY.

PROPELLING DEVICE.

1,197,766.

Specification of Letters Patent. Patented Sept. 12, 1916.

Application filed July 3, 1915. Serial No. 37,860.

To all whom it may concern:

Be it known that I, BRUNO SCHMELZER, a subject of the Emperor of Germany, and a resident of Jersey City, in the county of 5 Hudson and State of New Jersey, have invented certain new and useful Improvements in Propelling Devices, of which the following is a specification.

Modern aeronautics have created a demand for propelling devices resulting in an unusual study of aerodynamics and the development of mechanism for moving a body through an elastic fluid.

The present invention relates generally to 15 this class of mechanism, more particularly, however, to those of the rotary propeller type, and its purpose is to employ an element, which resembles in shape the concho-spiral shells of certain monovalve *Mollusca*, forming a fluid impeller of great simplicity 20 having a high degree of efficiency.

In the drawings, illustrating a few of the constructions;—Figure 1, is a vertical cross section of one form of the mechanism, Fig. 25 2, is a front elevation, viewed from the right hand side of Fig. 1, Fig. 3, is a plan view of the invention, Fig. 4, is a side elevation of one form of the propeller, and Figs. 5, 6, 7 and 8 are views respectively similar to 30 the corresponding views Figs. 1 to 4, inclusive, of a modified construction of the invention.

The structure comprises a support 1, movable on rollers or casters 2. It is understood 35 that the structure shown, is intended as an equivalent of any vehicle moving on roadways, tracks, or otherwise, including boats and vessels on water, and airships of the lighter-than-air, as well as heavier-than-air 40 type. The support carries a pair of brackets 3, 4, having bearings 5, 6 at their upper ends for a shaft 7, to which there is secured the propeller 8. The latter is rotatable in a casing 9, located in front, and embracing 45 approximately one entire half of the space through which the propeller rotates. The casing may be bounded by spherical, paraboloidal, or otherwise curved, surfaces, two forms of which are shown in the several 50 figures of the drawings. The casing is secured to and carried by the brackets, 3, 4,

through fastening means 10, 11, and a bracket 12 may form an additional support. The shaft 7 is provided with a pulley 13, which is rotated by means of a belt 14, or 55 otherwise, from a prime mover 15.

The essence of the invention rests in the peculiar shape and construction of the propeller 8. One of its simple forms is shown in Figs. 5 to 8, inclusive, and comprises two 60 or more members 16, 17, similar to a truncated cornucopia, or the concho-spiral shell of monovalve *Mollusca*. The outer, wider openings 18, 20, of one member, and the inner, smaller openings 19, 21, of the other 65 member, are preferably located in the same axial plane. When more than two members are employed, these respective openings are then located in corresponding angularly spaced-apart axial planes. 70

Figs. 1 to 4, inclusive, illustrate the members, divided into a plurality of overlapping scale-like elements 22, 23, decreasing in size from the larger, toward the smaller opening of each member, separated by open 75 spaces 24, 25, as clearly shown in Fig. 1, each element being held in its respective position, by flat circular plates rigidly attached at their outer sides, the plates being provided with hubs keyed to the shaft 7. 80

When rotation is imparted to the propellers 8, the effect is to force the structure to move in a direction opposite to the thrust of the propellers, the force being proportionate to their speed and magnitude. 85

Having thus described my invention, what I claim as new and desire to secure by Letters Patent, is:—

1. In a vehicle, the combination with a truck, a power source and a shaft driven 90 thereby, of a pair of conchoidal vanes secured to said shaft at opposite points thereon, and a casing fixed to said truck partially enveloping said vanes.

2. In a vehicle, the combination with a 95 truck, a power source and a shaft driven thereby, of two diametrically opposite conchoidal vanes of constantly decreasing internal area secured to said shaft, and a fixed shield having an open front extending past 100 the axial center of said shaft.

3. In a vehicle, the combination with a

wheeled truck, a power source and a shaft
driven thereby, of a pair of vanes each com-
prised of a plurality of overlapping con-
choidal segments, said vanes being oppo-
5 sitely disposed upon said shaft, and a casing
fixed to said truck having lateral extensions
passing the center of rotation of said vanes.

Signed at New York, in the county of
New York, and State of New York, this
19th day of June A. D. 1915.

BRUNO SCHMELZER.
